UNITED STATES PATENT OFFICE.

WILLIAM POPE, OF ROCKVALE, TENNESSEE.

GATE.

1,255,634.

Specification of Letters Patent.

Patented Feb. 5, 1918.

Application filed March 15, 1917. Serial No. 155,019.

To all whom it may concern:

Be it known that I, WILLIAM POPE, a citizen of the United States, residing at Rockvale, in the county of Rutherford and State of Tennessee, have invented certain new and useful Improvements in Gates, of which the following is a specification.

This invention relates to gates and has particular reference to gates which may be opened or closed from a remote point so that they may be operated by a person upon horseback or in a vehicle without dismounting. The invention seeks to provide means whereby the gate will be held in its open position so that it will not be prematurely closed and also to permit the closing of the gate without requiring the passerby to alight. A further object of the invention is to provide means for holding the gate in its closed position in order that it may not be opened by live stock. Other objects of the invention will appear as the description of the same proceeds and the novel features will be particularly pointed out in the claims following the description.

The invention is fully illustrated in the accompanying drawings in which:

Figure 1 is a perspective view of a gate embodying my improvements;

Fig. 2 is a plan view of the gate in its closed position;

Fig. 3 is a detail view of the means for holding the gate in an opened position.

In carrying out my invention, I set up, at opposite sides of the road, posts 1 and 2, the post 1 being a hinge post and the post 2 being a latch post. The gate proper consists of a plurality of rails or longitudinal bars 3 connected at their ends and at intermediate points by posts 4 and reinforced by a diagonal brace 5 which will resist any tendency of the gate to sag. One of the posts 4 is equipped with hinge members 6 adapted to engage pivot pins or pintles 7 on the hinge post 1 whereby the gate will be free to swing in a horizontal plane to either side. The intermediate posts or stays 4 are extended above the top rail 3 of the gate and to the upper ends of these extended posts or stays, I secure a beam 8 which extends upwardly over and beyond the hinge post and has a counter-weight 9 secured to its rear end whereby the gate will be counterbalanced and permitted to swing freely when operated. The provision

of this counter-weight 9 further aids in counteracting any tendency of the gate to sag, as will be readily understood.

Slidably resting on some of the intermediate rails 3 of the gate are latches 10 which are adapted to engage suitable sockets provided therefor in the latch post 2. A swinging latch bar 11 is pivoted at its lower end upon one of the rails 3 and has its upper end extended above the uppermost rail and the beam 8, as clearly shown in Figs. 1 and 2. The intermediate portions of the latch bar 11 have pin and slot connections with the latches 10, as shown at 12, whereby when the latch bar is swung about its pivoted lower end, movement will be imparted to the latches to release them from or project them into the sockets in the latch post. A spring 13 having its ends secured respectively to the latch bar 11 and the front post or stay 4 of the gate serves by its contraction to hold the latches in a projected position so that they will be normally in engagement with the sockets, as shown in Fig. 2. To the uppermost rail of the gate, between the front end of the same and the upper end of the latch bar 11, I secure brackets or posts 14 which project above the gate and between the upper ends of the said brackets or posts, I pivotally mount a latch 15 which is adapted to oscillate in a vertical plane, a spring 16, disposed between the rear portion of the latch and the upper portion of the gate, serving to hold the forward portion of the latch normally lowered so that it will ride upon the guide 17 and enter a notch 18 at the center of the same. The guide 17 may be of various forms, but is illustrated as a bar secured to the latch post 2 at the upper end of the same and having its upper edge beveled or made convex at its ends so that it may be readily engaged by the ends of the latch 15 and direct the same over the end of the latch post so that it will properly engage the notch 18. The said latch 15 has its rear portion extended a distance approximately equal to the throw of the upper end of the latch bar 11 and at the upper end of said latch bar is a roller 19 which is adapted to ride upon the upper edge of the rear portion of the latch so that if the latch bar be drawn toward the hinge post the rear end of the latch 15 will be depressed and, consequently, the front end thereof released from 110

the notch 18 and the latches 10 will also be slid from the latch post and released from their engagement therewith.

A lever 20 is fulcrumed upon the gate between the latch bar 11 and the hinge post and a compression spring 21 is connected with the gate and the said lever so as to normally project the lever toward the latch bar. The upper end of this lever projects above the beam 8 and is connected with the upper end of the latch bar 11 by a coupling 22. A pair of operating cables 23 are secured to the upper end of the lever 20 and extend rearwardly therefrom to pass around the guide pulleys 24 in rear of and above the hinge post and then extend in opposite directions along the side of the road to have their free ends depend from pulleys or rollers 25 at the outer ends of beams 26, the said beams being rigidly secured at their inner ends to the hinge post 1 and also connected by a brace bar 27 which has its ends secured to the beams and its intermediate portion secured rigidly to the said post. The guide pulleys 24 are mounted upon a plate or support 28 secured upon the rear end of the beam 8 and are disposed in pairs, as shown, the members of each pair being disposed substantially parallel with the vertical plane of the gate and a suitable cover 29 being disposed over the rollers to protect them from the action of the weather. As shown most clearly in Fig. 4, each cable passes from the lever 20 to the guide roller 24 which is nearer the hinge post and is then carried between said roller and the adjacent roller, after which it passes across the plane of the gate and in rear of the rearmost roller of the pair of rollers at the opposite side of the gate, thence passing out to the guide roller 25, as shown and as will be readily understood. The outer portion of the beam 8 is supported by a bracket or yoke 30 which has its lower end journaled in a bracket 31 secured upon the upper end of the hinge post 1 so that the yoke may turn with the beam 8 and the gate and thereby firmly support the outer end of the beam and the parts mounted thereon whether the gate be opened or closed. It will be readily understood that if a pull be exerted upon the extreme outer end of one of the cables 23, the said pull will be imparted directly to the lever 20 and thence transmitted through the coupling 22 to the latch bar 11 so that the latches 10 and 15 will be released. The continuation of the pull upon the cable will then act laterally upon the lever 20 so as to turn the gate upon its hinge connection with the hinge post and cause it to swing away from the operator to the side of the road. After the operator has passed beyond the gate, a pull is exerted upon the previously inactive cable 23 and the gate will be returned to its closed position, the latches au-

tomatically engaging the latch post as the hold upon the cable is released.

Upon the beams 26, intermediate the ends thereof, I secure brackets or supports 32 to which I pivotally attach dogs 33 having holding ribs 34 at their free ends. A spring 35 is connected to each dog and its support and by its compression serves to hold the dog normally in a lowered position. Upon the upper side of each dog is a pair of lugs 36 in and between which is mounted a guide roller 37, the operating cable 23 passing under the said roller, as clearly shown. It will also be readily noted that the said guide roller and the dog upon which it is mounted are disposed below a horizontal plane passing through the guide rollers 24 and 25 so that when a pull is exerted upon the operating cable, the cable will be shortened between the said rollers 24 and 25 and, consequently, will exert an upward pull upon the roller 37 so as to lift the dog 33 against the force of the spring 35. Upon each side of the gate is a keeper plate 38 having an upstanding lip 39 which is adapted to ride against and under the outer end of the dog 33 and slip into engagement behind the lip 34 thereon, as shown in Fig. 5, so that when the gate is opened one of the keeper plates will be engaged by the proper dog 33 and premature releasing or closing of the gate will be prevented.

It is thought the operation of the gate will be readily understood from what has been said. It may, however, be briefly summarized. A pull being exerted upon either cable 23, the lever 20 will be drawn rearwardly and a pull exerted through the coupling 22 upon the upper end of the latch bar 11, thereby swinging said latch bar toward the hinge end of the gate. The upper edge of the rear portion of the latch 15, when the gate is closed as shown in Fig. 2, extends across the arc described by the upper end of the latch bar 11 so that when the latch bar is drawn rearwardly, as just stated, the roller 19 will depress the rear end of the latch 15 and lift said latch out of its engagement with the notch 18. The rearward movement of the latch bar 11 will also withdraw the latches 10 from the latch post 2 so that the gate will be free to swing. The continued pull upon the cable 23 will then act laterally upon the lever 20 and swing the gate away from the operator toward the side of the road, carrying the keeper plate 38 into engagement with the dog 33 so that the gate will be held in open position. When the keeper plate 38 impinges against the end of the dog 33, in the event that straightening of the cable 23 has not lifted the dog beyond the path of the keeper plate, the spring 35 will yield so that the dog will ride over and into engagement with the keeper plate, as shown in Fig. 5. The operating

cable is then released and the driver or other person proceeds on his way. After passing the gate, the formerly inactive cable 23 is pulled so that the dog 33 will be withdrawn from the keeper plate 38 and a pull then exerted laterally upon the lever 20 to return the gate toward the latch post. The cable may be released after the gate starts its return swing as the momentum of the gate will be sufficient to carry it to the closed position and the latches 10 should have their working ends beveled or otherwise shaped to ride upon the latch post 2 into engagement with the sockets in said post so that the gate will be automatically latched upon reaching the closed position. It will be noted that the mounting for the guide rollers 24 swings with the gate so that the direction in which the cables 23 act upon the gate relative to the gate is the same in all positions thereof.

A hood 40 is secured upon the brackets 14 and extends over the same and the latch 15 so that said elements, together with the latch bar, will be protected from the weather and, consequently, will not be rendered inoperative by an accumulation of snow or ice or dirt. This hood 40 will preferably be a sheet metal plate of an inverted U-shape 30 in cross section and a similar hood 41 is secured over each of the dogs 33 and parts co-acting therewith as well as over the guide rollers 25. The hoods over the last-mentioned guide rollers, however, are omitted from the drawings for the sake of clearness.

A cable 42 is secured to and extends between the depending free ends of the operating cables 23 to permit the gate to be opened and closed from the same side. After the gate is opened in the described manner, a pull is exerted upon the cable 42 and the gate will then swing to closed position. This arrangement is advantageous when it is desired to have stock pass from one to another field.

My gate is very simple and compact in the construction and arrangement of its parts and will operate easily and smoothly at all times. When in either the open or closed position it will be firmly held against premature release but may be easily released when it is desired to permit the passage of

any person or close the gate after the person has passed.

Having thus described the invention, what is claimed as new is:

1. The combination of a supporting structure, a gate mounted for horizontal swinging movement on the supporting structure, a dog pivoted on said structure and spaced laterally from the gate, an open guide upon the upper side of the dog, guides on the supporting structure at opposite sides of the dog and above the horizontal plane of the same, an operating cable connected with the gate and passing around the last-mentioned guides and through the guide on the dog and acting on said guide to raise the dog, a spring bearing upon the dog and opposed to said cable, and a keeper on the gate arranged to ride under and engage the dog in opposition to the spring.

2. The combination of a hinge post, a latch post, a gate mounted upon the hinge post for swinging movement, a latch upon the gate adapted to engage the latch post, guides disposed above and in rear of the hinge post and supported from the gate, guides supported beyond and at opposite sides of the gate in the same horizontal plane as the first mentioned guides, dogs supported between said guides and below the plane of the same, means on the gate to engage said dogs, and operating cables connected with the latch on the gate and passing around the guides and arranged to act on said dogs whereby to release the gate from either its open or closed position and swing it from opened to closed position or vice versa.

3. The combination of a swinging gate, a latch pivoted upon the gate and having its rear portion extending normally upward, a latch bar pivoted upon the gate with its upper end describing an arc intersecting the upper edge of the rear portion of the latch in the normal position of the same, the upper end of said latch bar being arranged to bear upon the upper edge of the latch, a lever mounted upon the gate, a connection between said lever and the latch bar, and means connected with the lever for releasing the latch and swinging the gate.

In testimony whereof I affix my signature.

WILLIAM POPE. [L.S.]
